DESIGN FOR A THERMOMETER CASING

Edward P. Dobrin, New York, N. Y., assignor to
Weksler Thermometer Corporation, New York,
N. Y., a corporation of New York

Application March 14, 1946, Serial No. 127,486

Term of patent 14 years

(Cl. D52—7)

To all whom it may concern:

Be it known that I, Edward P. Dobrin, a citizen of the United States, residing at New York city, in the county of New York and State of New York, have invented a new, original, and ornamental Design for a Thermometer Casing, of which the following is a specification, reference being had to the accompanying drawing, forming a part thereof.

Figure 1 is a top view of a thermometer casing embodying my new design;

Figure 2 is a front view;

Figure 3 is a side view; and

Figure 4 is a longitudinal section taken along line 4—4 of Figure 2.

I claim:

The ornamental design for a thermometer casing, as shown.

EDWARD P. DOBRIN.
